RAIL DRILL

Henry H. Talboys and Helmer E. Erickson, Milwaukee, Wis., assignors to Nordberg Manufacturing Co., Milwaukee, Wis., a corporation of Wisconsin

Application August 26, 1948, Serial No. 46,248

17 Claims. (Cl. 77—8)

1

Our invention relates to an improvement in rail drills and has for one purpose to provide an improved drill for drilling holes in railroad rails.

Another purpose is to provide a light and easily operated rail drill structure.

Another purpose is to provide an improved drilling or drill actuated mechanism.

Another purpose is to provide improved means for adjusting the drill or bit support and for accurately positioning the aperture to be drilled.

Other purposes will appear from time to time in the course of the specification and claims.

The invention is illustrated more or less diagrammatically in the accompanying drawings, wherein:

Figure 1 is a perspective view;

Figure 2 is a side elevation with parts broken away;

Figure 3 is an end elevation on an enlarged scale with parts in section;

Figure 4 is a section on the line 4—4 of Figure 3;

Figure 5 is a section on the line 5—5 of Figure 4; and

Figure 6 is a partial perspective view on a scale larger than Figure 1.

Like parts are indicated by like symbols throughout the specification and drawings.

Referring to the drawings 1, 1 indicate track rails with vertical webs 2 and top rail heads 3. Mounted upon the head 3 of one rail is a supporting structure which includes a pair of parallel, transversely extending rail engaging supports 4, 4. These are shown as of rectilinear tubing, but may be of any suitable shape. Extending upwardly from each is a vertical post or rod 5, the rods being connected by a top yoke 5a, resting upon and surrounding their upper ends. Vertically adjustable upon the rods 5 is a supporting frame which includes a cross-piece 6 apertured to guide on the rods 5. It includes depending parts 7 having outwardly extending eyes 8, 9, through which the rod 5 also pass. This frame is vertically adjustable by the employment of an adjusting screw 10, having an operating handle or cross-piece 11 and having oppositely threaded portions 12 and 13, corresponding with nuts 12a and 13a which are confined in appropriately formed recesses in the members 5a and 6 respectively.

14 is any suitable lock nut, with a manual handle 15 for locking the parts in adjusted position. The cross-piece 6 and its downward extensions 7 are unitary with a base portion 20 having a substantial extension transversely on

the track. Mounted on the base is any suitable power unit, such as the internal combustion engine generally indicated at 21.

Laterally extending bracket members 22 are apertured to receive a rod 23 which spans the two rails and which has an offset end portion 24 provided with any suitable insulating member 25 for engaging the opposite rail of the track. One of the brackets 22 is provided with an aperture 26 through which a cotter pin 27 may pass. The rod or tube 23 is properly apertured to receive the cotter with the offset 24, either in the upper position, as shown in Figure 1, in the diametrically opposed downward position, or in a position 90 degrees from that shown.

The entire structure is traversable transversely of the rails. Normally fixed in relation to the rail is the rail engaging abutment or fork 30, which includes an upper portion 31 movable lengthwise in relation to the base 20, the base 20 being slotted longitudinally along its bottom, as at 32, to permit the downward extension of the upper part of the fork 30. The fork 30 includes two tines 33 located each side of the below-described drill bit. The upper portion 31 of the fork is screw-threaded to receive the screw 34 which is rotatable by the exterior handle 35 and which is provided with any suitable bearing assembly 36 at its outer end. 37 is any suitable one-way or over-running handle which is rotatable in relation to the screw 34 in one direction only, the direction of permitted rotation being suitably controlled so that it can be used to rotate the screw in either direction.

Extending downwardly from the forward end of the base 20 is a knuckle or downward projection 40 in which is rotatably mounted a socket member 41 having a tapered bore 42 which receives bit holding elements 43 and the drill bit.

44 is any suitable knockout rod. The socket member 41 has secured to it a ratchet-toothed wheel 45, the teeth being formed to receive dogs 46 on arms 47, each arm terminating at its upper end in an eye 48 surrounding an eccentric 49 on the driven shaft 50. The constant tightening of the threads of the ratchet 45 and the spindle 41, due to the operation of the machine, would make it very difficult to unscrew the ratchet 45, when necessary to replace it. Therefore, we prefer to use any suitable fusible washer 45a. By melting the fusible washer, the pressure between the threads can be released. Springs 51 normally urge the dog 46 against the teeth of the wheel 45, the teeth being formed, however, to underride the dogs when the wheel is given a clockwise direction of movement, referring to the

position of the parts as shown in Figures 3 and 6. The springs 58 may extend through an aperture 52 in the side wall of the downward extension 40 and may be outwardly secured to any suitable bracket 53.

Positioned above the right end of the base 20, referring to the position of the parts as shown in Figure 2, is a pressure frame 55 pivoted as at 56 and provided with an opposite end 57 normally downwardly thrust by a spring 58, coiled about the headed rod or bolt 59, with its upper nuts 60, 61. Gripped between the two nuts is any suitable guard plate 62. It will be understood that the upper part of the rod or bolt 59 is screw-threaded and that its compression may be adjusted by varying the position of the nuts 60, 61. Its head 63 may be employed to position the bracket 53.

The shaft 50 is rotatable in any suitable bearing assemblies 65, which normally are seated in appropriately formed seats 66 in the upper portion of the member 55. They are normally upwardly thrust against their seats by any suitable spring or springs 67, as shown in the upward extensions or lugs 68 of Figure 4. The shaft 50 as shown, in Figure 4, is provided with eccentrics 49, which are surrounded by suitable ball bearing assemblies 70 within the eyes 48. In order to drive the shaft 50, we provide the following connection with the engine.

80 indicates the end of an engine or motor-driven shaft and 50a an inward extension of the shaft 50. The two shafts extend into the opposite ends of a tubular member 81, shown as rectangular in cross-section and as having, in one corner, a longitudinally extending bar 81a. Positioned upon shaft members 50a and 80 and keyed to them to prevent relative rotation are members 82, each having a rectangular portion 83 and a circular portion 84. One of the members 82 is keyed to each of the shaft ends. A powerful torsion resisting drive member is thereby provided which permits a reasonable degree of variation in the alignment of the centers of rotation of the two shafts.

It will be realized that whereas we have described and illustrated a practical and operative device, nevertheless many changes may be made in size, shape, number and disposition of parts. We therefore wish our description and drawings to be taken as in a broad sense illustrative or diagrammatic, rather than as limiting us to our precise showing.

The use and operation of the invention are as follows:

We illustrate herein a simple, light and compact, but efficient, rail drill structure. The drill bit X is pawl driven. We show two pawls or dogs which, in response to rotation of the shaft 50, rotate the bit X through the toothed wheel or chuck ratchet 45. As one pawl or dog rotates the wheel ratchet 45 in clockwise direction, the other pawl slides over the adjacent tooth into position for an ensuing thrust. The drilling point may be adjusted by rotation of the adjusting screw 10. The spring 58 serves as an overload release. Should the rotation of the crank or eccentric 49 approach infinity under load, the spring 49 will compress under the load and prevent damage to the structure by too much force between member 55 and ratchet 45. Also, the bit cannot be fed beyond the capacity of the motor. The overload release is also equipped or assisted by the flexible coupling, which includes the rectangular tubular member 81, which per-

mits and adapts itself to upward normal movement of the member 55 about its center 56 and against the thrust of the overload release spring 58.

Whereas the bit is motor-driven, the feed is manual. Rotation of the shaft or screw 34 moves the base 20 bodily transversely of the rails. However, it does not engage the rails themselves, the rail contact being through the members 4. The cross-rod 23 also moves during the feeding movement of the device, but its contact member 25 is of sufficient length to maintain the necessary supporting contact with the opposite rail throughout the drilling operation.

In use, and assuming that the screw 10 has been rotated to set the bit X at the proper height, rotation of the screw 32, for example for manual rotation of the handle 35, may be employed to move the base 20 to the left, referring to the position of the parts in Figure 2. The drill bit X is rotated by the motor 21 through the above-described drive and as the operator manually feeds the base 20 to the left, the drill bit X advances into the metal. Any overfeeding beyond the capacity of the motor simply results in an upward lifting of the member 55 against the spring 58. The shaft 50 maintains its proper relationship to the member 55, being upwardly thrust by the springs 67. When the overload terminates, the spring 55 is effective to return the parts to initial position and the flexible coupling 81 permits the relative changes in position of the shafts 80 and 50a.

The machine may be made of light material, such as aluminum, and may easily be handled, being a one-man machine. It may readily be lifted. We illustrate, for example, a tubular handle 90 on brackets 91 which are shown as mounted on the rods 5. The lightness and ease in handling make it easy for one man to operate the drill and to remove it from the rails when a train approaches. No part of the machine rests on the ties. The cross-bar, support or stabilizing bar 23 maintains the machine in level position when drilling. The fact that it can be reversed with the offset portion either up or down or, if desired, sideways, permits the operator easily to maintain the machine level on rail when the opposite rail is of a different height.

With reference to the operation of the drill mechanism, we illustrate the particular embodiment of our invention showing diametrically opposed eccentrics 49, each of which controls or actuates a conveying dog or pawl 47. When one of the members 47 is at the end of its conveying movement and in contact with one of the ratchet teeth, the other member 47 is withdrawn into position to engage another tooth. In the device as herein shown and operated, it is ready to engage the next tooth and to convey it forwardly one step before it, in turn, overrides the next following tooth. Thus the drill bit is rotated step by step, but at a high rate of speed, and we find that the step by step rotation provides a very effective cutting movement of the bit.

It will be understood that when the operator speeds up the device to beyond its cutting capacity, or when the bit strikes overhard material, then the safety must come into play and the springs 58 permit a lifting position. In Figure 3 the spring 58 is shown as holding the parts in the normal drilling position, whereas in Figure 6, the spring 58 is compressed and the member 57 of the yoke 55 has been raised, the yoke rotating about its pivot 56. Meanwhile, the springs 67

keep the bearing assembly in proper position and the flexible connection 81 prevents any interruption of the drive and avoids any strain on the driven shaft.

It should also be kept in mind that when the yoke 55 is in the release position of Figure 6, with the shaft 59 upwardly raised by the springs 67, the pawls or dogs 47, with their effective ends 46, are somewhat upwardly withdrawn and the next tooth will not be caught or thrust against until the device is again operating normally and until the lower tooth has been freed from its strained engagement with the pawl 45.

As to the flexible connection, the member 81a is a spacing bar which keeps the square members 82 at a proper separation. They are of course held against rotation by their squared form. In assembling the connection, the members 82 may simply be slipped into the square tube 81 or the square tube 81 may be slipped over one of them, the other being thereafter inserted into the square tube in proper operating relationship.

We claim:

1. In a drill structure for drilling track rails, a frame, supporting means for supporting said frame in position transversely across and above a track rail, a drive shaft on said frame mounted for rotation about a horizontal transverse axis, located above the rail top, and means for rotating it, a drill spindle on said frame mounted for rotation about an axis generally parallel with but below the axis of the drive shaft and in horizontal alignment with the web of the rail, and means for driving said drill spindle including an eccentric on said drive shaft, a ratchet wheel connected to said spindle and a pawl surrounding and depending from said eccentric, said pawl having a ratchet end formed and adapted to engage and thrust against the teeth of the ratchet wheel in response to rotation of the eccentric, and yielding means for urging said pawl against the teeth of the ratchet wheel.

2. The structure of claim 1 characterized by and including a plurality of eccentrics angularly separated on the drive shaft and a plurality of pawls surrounding and depending from said eccentrics, each having an eye surrounding one of said eccentrics.

3. The structure of claim 1 characterized by and including a releasable support for the drive shaft formed and adapted to permit the drive shaft to recede upwardly in response to predetermined excess resistance to the thrust of the pawl against the ratchet wheel.

4. The structure of claim 1 characterized by and including a releasable support for the drive shaft formed and adapted to permit the drive shaft to recede upwardly in response to predetermined excess resistance to the thrust of the pawl against the ratchet wheel, and yielding means of sufficient strength normally to hold said releasable support in predetermined operating position.

5. The structure of claim 1 characterized by and including motor means mounted on the frame, and a torque tube extending between the motor means and the drive shaft.

6. The structure of claim 1 characterized by and including motor means mounted on the frame, and a non-cylindrical torque tube extending between the motor means and the drive shaft, the motor means and the drive shaft having connecting abutments extending into the opposite ends of said torque tube.

7. The structure of claim 1 characterized by

and including motor means mounted on the frame and a rectangular torque tube extending between the motor means and the drive shaft, the motor means and the drive shaft having generally cylindrical abutments extending into the opposite ends of the torque tube.

8. In a drill structure for drilling track rails, a frame adapted to be positioned transversely across and above a track rail, a motor on said frame, a drive shaft on said frame and a yielding bearing support therefor adapted normally to hold said drive shaft with its axis in a predetermined horizontal position in a plane transverse to the track, a yielding release adapted to permit upward movement of said bearing support in response to predetermined overload, a drill spindle rotatably supported on said frame for rotation about an axis generally parallel with but below the axis of the drive shaft and in horizontal alignment with the web of the rail, and a ratchet and pawl driving connection between the drive shaft and the drill spindle.

9. The structure of claim 8 characterized by and including a driving connection between the motor and the drive shaft effective throughout a substantial range of displacement of the axis of the drive shaft during the release of the bearing support.

10. The structure of claim 8 characterized by and including a torque tube driving connection between the motor and the drive shaft.

11. In a drill structure for drilling track rails, a frame, supporting means for supporting said frame in position transversely across and above a track rail, a drive shaft on said frame mounted for rotation about a horizontal, transverse axis located above the rail top and means for rotating it, a spindle shaft mounted for rotation about an axis generally parallel with but below the axis of the drive shaft and in horizontal alignment with the exterior of the web of the rail, means for maintaining a driving connection between said drive shaft and said spindle shaft including a rotatable head generally axially aligned with said drive shaft but spaced outwardly therefrom, a driving connection between said head and the spindle shaft, and a flexible coupling between said drive shaft and said head.

12. The structure of claim 11 characterized in that the drive shaft and the rotatable head have portions extending into opposite open ends of a tubular driving connection, and including spacing means within said tubular driving connection, adapted to maintain a predetermined spacing between said portions.

13. The structure of claim 11 characterized in that the driving connection between the head and the spindle shaft includes one or more eccentrics rotatable with the head, and downwardly depending pawls surrounding said eccentrics, the spindle shaft having a ratchet wheel adapted to receive the lower ends of said pawls.

14. The structure of claim 11 characterized by and including an eccentric dog-and-tooth connection between the head and the spindle shaft, and yielding means formed and adapted normally to hold the rotatable head at a predetermined distance from above the spindle shaft while permitting an upward recession of the head in response to predetermined conditions of excess stress.

15. The structure of claim 11 characterized by and including supporting means for the head including a movable yoke overlying an upper portion of the head, and yielding means tending

normally to hold the yoke against movement but adapted to permit an upward movement of the yoke under predetermined conditions of excess resistance.

16. The structure of claim 11 characterized by and including supporting means for the head including a movable yoke overlying an upper portion of the head, yielding means tending normally to hold the yoke against movement but adapted to permit an upward movement of the yoke under predetermined conditions of excess resistance, and yielding means adapted normally to urge the head against an overlying portion of the yoke.

17. In a drill structure for drilling track rails, a frame including portions overlying and resting upon a track rail, a drive shaft on said frame mounted for rotation about a horizontal transverse axis located at a level above the rail top and means for rotating it, a spindle shaft mounted for rotation about an axis generally parallel with but below the axis for the drive shaft and in horizontal alignment with the exterior of the web of the rail, means for maintaining a driving connection between the drive shaft and the spindle shaft including a rotatable head generally axially aligned with the drive shaft but spaced outwardly therefrom, an eccen-

tric dog-and-tooth connection between the head and the spindle shaft, a flexible coupling between the drive shaft and the head, and yieldable release means adapted normally to hold the head at a predetermined distance above the spindle shaft but adapted to permit its upward recession therefrom in response to predetermined resistance to drilling.
